UNITED STATES PATENT OFFICE.

FRANK NELSON OLCOTT, OF NEW YORK, N. Y., ASSIGNOR TO BLACK AND BOYD MANUFACTURING COMPANY, OF NEW YORK, N. Y., A CORPORATION OF NEW YORK.

DESIGN FOR AN ELECTRIC BRACKET.

43,888.

Specification for Design.

Patented Apr. 22, 1913.

Application filed April 10, 1912. Serial No. 689,908. Term of patent 3½ years.

To all whom it may concern:

Be it known that I, FRANK NELSON OLCOTT, a citizen of the United States, and a resident of the borough of Manhattan, city, county, and State of New York, have invented a new, original, and ornamental Design for an Electric Bracket, (Case A,) of which the following is a specification, reference being had to the accompanying drawing, forming a part thereof.

The drawing represents a front elevation of the new design.

The essential features of the design comprise the centrally located wreath support-

ed by the double ribbon forming a knob at the top; the lower ends of the ribbon carrying tassels; and arms, ornamented with leaves, for carrying lamps, springing out of the center of the wreath and crossed by bands at the center.

I claim:

The ornamental design for an electric bracket, as shown and described.

FRANK NELSON OLCOTT.
